DESIGN FOR A BOTTLE

Thomas D. D'Addario, Long Island City, N. Y.,
assignor to Bostonia Beverages, Inc., Natick, Mass.

Application July 1, 1938, Serial No. 78,223

Term of patent 14 years

To all whom it may concern:

Be it known that I, Thomas D. D'Addario, a citizen of the United States, residing at 33-11 28th Ave., Long Island City, in the county of Queens and State of New York, have invented a new, original, and ornamental Design for a Bottle, of which the following is a specification, reference being had to the accompanying drawing, forming part thereof.

Figure 1 is a side view in elevation of a bottle, showing my new design. The reverse side of the bottle is of the same design.

The opposite side of the bottle is substantially the same as the side shown in the drawing.

I claim:

The ornamental design for a bottle, as shown and described.

THOMAS D. D'ADDARIO.
